UNITED STATES PATENT OFFICE.

LEONARD P. MOSHER, OF COLLAMER, NEW YORK.

COMBINED LOAD BINDER AND ELEVATOR.

SPECIFICATION forming part of Letters Patent No. 247,845, dated October 4, 1881.

Application filed August 18, 1881. (No model.)

To all whom it may concern:

Be it known that I, LEONARD P. MOSHER, of Collamer, in the county of Onondaga, in the State of New York, have invented new and useful Improvements in Combined Load Binder and Elevator, of which the following, taken in connection with the accompanying drawings, is a full, clear, and exact description.

10 The nature of this invention consists in a novel combination and arrangement with the rack or box of a wagon of a rope extended across one end thereof, and fixed at its extremities to the opposite end of the same, with a slack on the intermediate portions of the rope and a roller connected to said intermediate portions of the rope and adapted for the application of a wrench or lever, and of central elevating ropes, as hereinafter more fully described, and specifically set forth in the claims.

15 In the accompanying drawings, Figure 1 is an isometric view of my invention, showing its application as a load-binder. Fig. 2 illustrates its operation as an elevator of the rack, and Fig. 3 is an enlarged detached view of the roller used in connection with the binding and elevating ropes.

20 Similar letters of reference indicate corresponding parts.

25 R represents an ordinary hay-rack of a wagon.

30 a is a rope, which is passed across the under side of one end of the rack, as shown at b, so as to be movably connected thereto. From thence the two end portions, c c, of the rope are 35 extended nearly or quite parallel toward the opposite end of the rack and firmly secured thereto, the portions c c having sufficient slack to pass over the top of the load of hay or other 40 substance placed on the rack R.

45 r is a roller of a length to reach across the top of the load. It is movably connected to the sections c c of the rope, at about midway the length of the rack, by passing the rope through holes h h, extended transversely through the roller. The center of the roller r is provided with a staple, i, or other suitable means for connecting thereto the central part of the section b of the rope, which, after the sections 50 c c of said rope have been properly adjusted upon the load, is drawn up and connected to

the said staple, as shown in Fig. 1 of the drawings. A square or hexagonal collar, n, rigidly secured to the roller r, admits of the application of a wrench or lever, l, for turning the 55 roller and winding upon the same the several sections of the rope a connected thereto, as aforesaid, thereby binding the load on the rack. By leaving the lever l connected with the collar n and carrying its free end underneath the 60 rope the roller is prevented from turning back and unwinding the ropes. When the rack is to be unloaded the lever l is made to release the roller r. The section b of the rope is then removed from the roller, and the roller moved 65 along the sections c c to the end of the rack. The rope can then be thrown off the load.

70 When it is desired to remove the rack from the wagon the side sections, c c, of the rope are drawn out until the section b is drawn tight across the end of the rack. The roller r is then moved into the center of the sections c c, and the slack portions of the rope at opposite sides of the roller are thrown upon pulleys P P, secured at a proper elevation and in a convenient position in the barn or wagon-shed. To the ends of the roller are then connected two ropes or chains, s s, which, in turn, are secured to a bar, d, extended across the under side of the rack R. Then by applying the lever l and 75 turning the roller r all the ropes a, s, and s are wound upon said roller, and the rack is thus lifted off the wagon, and can be elevated 80 as far as the length of the respective ropes will permit.

85 By fastening the roller r so as to prevent it from turning back the rack can be kept in its suspended elevated position.

When the rack is to be replaced onto the wagon, the wagon is placed directly under the 90 rack and the rack let down onto it by releasing the roller r, so as to unwind the several ropes. Then the ropes s s are taken off the ends of the roller, and the bar d is removed from under the rack and the rope a conveniently disposed around the exterior of the rack 95 preparatory to reloading the same.

Having described my invention, what I claim, 100 and desire to secure by Letters Patent, is—

1. The combination, with the rack R, of the rope a, having the section b extended across

one end of the rack and movably connected thereto, and the end sections, *c c*, secured to the opposite end of the rack with a slack on the rope, and the roller *r*, connected to the sections *c c*, and provided with means for connecting to said roller the central part of the section *b* of the rope, and adapted for the application of a lever or wrench for turning said roller, substantially as described, for the purpose set forth.

2. The combination, with the rack *R*, of the rope *a*, extended from end to end of the rack at the two sides thereof, with a slack on the intermediate portion, *c*, of the rope, the roller *r*, connected to said intermediate portion of the rope, and adapted for the application thereto, respectively, of a wrench or lever, and of the elevating-ropes *s s*, substantially as described and shown, for the purpose set forth.

3. The combined load binder and elevator,

consisting in the combination, with the rack *R*, of the rope *a*, having the section *b* movably connected across one end of the rack, and the end sections, *c c*, secured to the opposite end of the rack, with a slack on the said rope, and the roller *r*, connected to the sections *c c*, and provided with means for connecting to it respectively the center of the rope-section *b*, a wrench or lever, and the elevating-ropes *s s*, all substantially as described and shown, for the purpose specified.

In testimony whereof I have hereunto signed my name and affixed my seal, in the presence of two attesting witnesses, at Syracuse, in the county of Onondaga, in the State of New York, this 11th day of August, 1881.

LEONARD P. MOSHER. [L. S.]
